J. R. MARSHALL

CONDUCTOR SUSPENSION APPARATUS

Filed Oct. 5, 1925

UNITED STATES PATENT OFFICE.

JOHN R. MARSHALL, OF MCKEAN, PENNSYLVANIA.

CONDUCTOR SUSPENSION APPARATUS.

Application filed October 5, 1925. Serial No. 60,496.

This invention is designed to improve the manner of suspending electric conductors so that the same may be mounted and raised and lowered to their pole supports without the necessity of the linemen climbing the poles with the idea of facilitating the work as to the installation and also to permit of such operations with relation to the variation of the wires with less danger and greater convenience to the linemen. Features and details of the invention will appear from the specification and claims.

The invention is illustrated in the accompanying drawings as follows:

Fig. 1 shows a side elevation of the apparatus.

Fig. 2 an end elevation of the same.

Fig. 3. a sectional view of one of the hanger frames.

1 Fig. 1 marks the pole support which may be of any type of support for carrying electric conductors. A cross arm 2 is normally loose from the pole but is drawn and held in place by straps 3, one at each side of the pole with fingers 4 extending downwardly from the face of the cross arm. The cross arm is raised to position by a cable 5 which is secured to a strap 6 on the cross arm and extends over a pulley 7 carried by a bracket

25 8 at the top of the pole, the cable being secured on a cleat 8^a on the pole. A down-haul loop 9 is arranged below the strap 6 so that should there be any difficulty in the downward movement of the cross arm, or 30 it may be necessary to guide the cross arm to place an instrument may be placed in this loop for this purpose. With this construction the cross arm is raised and lowered at will from the base of the pole.

35 40 Line wires 10 and 11 are carried between the roller insulators 12, these insulators having the grooves 12^a which, as the insulators are opposingly placed, form the openings 12^b for the line wires. The insulators have 45 the trunnions 13 and the trunnions at the insides of the insulators extend into slots 14 in uprights 15. The uprights are secured between cross pieces 16 and 17 at the top and bottom of the frame respectively. The

50 outer trunnion of the lower insulators extends into a slot 18 on a post 19 secured between the cross pieces 17 and the trunnion on the outer side of the upper insulator extends into a slot 20 in a block 21. The 55 block 21 is secured to the block or post 19

by a hinge 22 and through the action of this hinge can be swung outwardly and this uncovers the trunnion of the upper insulator and permits the removal of this insulator and after the removal of the top insulator 60 the lower insulator may be moved upwardly, the trunnions 13 sliding in the slots 14 and 18 so that the lower insulator may be removed. In this way the wires may be placed in the insulators, the insulators in 65 their sockets, and the socket piece 21 swung to position, thus locking the insulators in place. In order to lock the piece 21 in its closed position a sliding bolt 23 is provided. This is slidingly carried under plates 24 on 70 a block 24^a arranged between the cross pieces 16. With the sliding plate or bolt 23 in its lower position and overlapping the socket piece 21 this piece is prevented from moving 75 outwardly and thus releasing the insulators. Locking catches 25 are provided which may be swung over the bolt 23 to lock it in place. A cable 26 is secured between the cross pieces 16 and extends over a pulley 27 carried by brackets 28 on the upper side of the 80 cross arm 2. The cable is secured by a cleat 29 in a convenient position toward the bottom of the pole. In this way the wires may be placed in the hanger frame and this drawn up to the cross arm, or lowered as 85 desired by means of the cable 26. Guide fingers 16^a extend from the cross arm over the hanger and these are provided with shoulders 16^b which engage the cross pieces 16 as the cable 26 is drawn taut, thus 90 securely locking the hanger in place under the cross arm.

A downward haul 30 is provided on the hanger being suspended from the cross pieces 17 and this facilitates the guiding of 95 the hanger to place and by means of an instrument from the ground.

In order to separate the line wires 10 and 11 a hanger similar to that used on the cross arm is threaded on to the line wires 10 and 11. This hanger is provided with a down-haul 30 and in every other respect is similar to the hanger used on the cross arm.

An alternative construction of hanger is shown in Fig. 2 in which the wires are arranged, one above the other. In this there are top and bottom cross pieces 32 and 33 and an intermediate cross piece 34. An upright strip 35 is secured between these cross pieces and has the trunnions' sockets 36. 110

Rigid block or socket pieces 38 carry the lower outer trunnions and hinged blocks 39 carry the upper trunnions, these blocks being secured to the lower blocks by hinges 40. The hinged block is locked by a slide 41 in the same manner as the slide 23. A cable 42 extends over a pulley 43 carried by a strap 44 on the cross arm and extends downwardly so as to be conveniently secured to the post. It will be readily seen that these hangers may be raised and lowered, a wire removed or replaced, or where there is a wire broken the hangers may be lowered and the splicing made and the wires again drawn to place. Thus the entire installation and maintenance of the line may be accomplished by the operation of the line-men from the ground relieving the present dangers and also adding to the convenience with which they may be operated.

What I claim as new is:—

1. In a conductor suspension apparatus, the combination of a pole support; an insulating frame; line wire insulators mounted in the frame; line wires on the insulators extending each side of the insulators and with slack; and a hoisting means leading from the support to the frame adapted to raise and lower the line wires at will.
2. In a conductor suspension apparatus, the combination of a pole support; a cross arm; means for hoisting and lowering the cross arm relatively to the support; an insulator frame on the cross arm; line wire insulators on the frame; and line wires on the insulators extending each side of the insulators and with slack.
3. In a conductor suspension apparatus; the combination of a pole support; a cross arm; means for hoisting and lowering the cross arm relatively to the support; an insulator frame on the cross arm; line wire insulators on the frame; line wires on the insulators extending each side of the insulators and with slack; and hoisting means leading from the cross arm to the insulator

frame adapted to raise and lower the wires from the cross arm at will.

4. In a conductor suspension apparatus, the combination of a pole support; an insulator frame; line wire insulators on the frame; line wires movably mounted on the insulators extending each side of the insulators, and with slack; and a hoisting means leading from the support to the frame adapted to raise and lower the frame at will.

5. In a conductor suspension apparatus, the combination of a pole support; an insulating frame; line wire insulators mounted in the frame; line wires on the insulators extending each side of the insulators, and with slack; a hoisting means leading from the support to the frame adapted to raise and lower the line wires at will; and a spreader on the line wires between the supports.

6. In a conductor suspension apparatus, the combination of a pole support; an insulating frame; line wire insulators mounted in the frame; line wires on the insulators extending each side of the insulators, and with slack; a hoisting means leading from the support to the frame adapted to raise and lower the line wires at will; and a spreader on the line wires between the supports comprising insulators on which the wires are movably mounted.

7. In a conductor suspension apparatus, the combination of a pole support; an insulating frame; line wire insulators mounted in the frame; line wires on the insulators extending each side of the insulators, and with slack; a hoisting means leading from the support to the frame adapted to raise and lower the line wires at will; and a spreader on the line wires between the supports comprising roller insulators on which the wires are movably mounted.

In testimony whereof I have hereunto set my hand.

JOHN R. MARSHALL.
